TOOL GUIDE FOR CABLE TOOL DRILLS

George R. Watson, Waukegan, Ill., assignor to
Bucyrus-Erie Company, South Milwaukee,
Wis., a corporation of Delaware

Application May 7, 1943, Serial No. 486,025

6 Claims.

(Cl. 255—11)

My invention relates to new and useful improvements in tool guides for cable-tool drills.

Such drills, per se, are well known.

In such drills a rope passes, from a winch drum on the main frame, around a heel sheave at or near the pivot of a spudding beam, thence under a sheave at the oscillating end of the spudding beam, thence over a sheave at the upper end of a mast, and thence vertically downward into the hole which is being drilled in the ground. At the lower end of this rope is a string of percussion drilling-tools. The spudding beam is oscillated by a pitman, actuated by a rotating crank.

As the rope is paid out to lower the tools into the hole, it is necessary that the tools be guided so as to start drilling the hole vertically. Accordingly there is usually provided on the mast of the drill, a gadget known as a tool guide.

Preferably the tool guide should be so constructed that it will open to admit the tools, rather than compelling them to be threaded through it from above. Similarly, and even more important, it should open so that the rope can be withdrawn or inserted while the tools are in the hole.

Also the tool guide serves as a better guide, if it be relatively long.

Accordingly it is the principal object of my invention to devise a tool guide which shall possess the above-mentioned desirable characteristics.

In addition to my principal objects, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description, the same reference number is applied to the same member or to similar members.

Figure 1 is a side elevation of a drill embodying my invention.

Figure 2 is an enlarged side elevation of the mechanism which actuates my tool guide.

Figures 3, 4 and 5 are enlarged front elevations of my tool guide, Figure 3 showing the guide closed, Figure 4 showing one half of the guide elevated and opened, and Figure 5 showing both sides opened.

Referring now to Figure 1, we see that 11 is

the main frame of a drill, supported by creeping traction mounting 12.

The frame 11 supports a mast 13 (called "derrick" in the art), a motor 14, a winch 15, a spudding gear 16, and associated driving connections, not numbered.

From the winch 15, a rope 17 runs around a heel sheave 18, thence under a spudding-sheave 19, thence over a sheave 20 at the top of the derrick 13, thence down to the drilling tools 21.

The spudding gear 16 is clutched to and unclutched from a drive connection with the motor 14, by means of a clutch (not shown).

The spudding-sheave 19 is mounted on the free end of a spudding beam 22, which in turn is pivoted on horizontal pivots 23 on the frame 11.

The spudding-beam is rocked up and down by the rotation of the spudding gear 16, acting through pitman 24.

20 The winch 15 is controlled by means of a conventional drive, clutch, brake, and hand-levers (not shown).

The operation of all these conventional parts will be readily understood.

25 So much for the setting of my invention. The tool guide 25, which is the subject of my invention, is mounted on the derrick 13.

For the details of this tool guide, let us now turn to Figures 2, 3, 4 and 5.

30 My tool guide is a belled hollow cylinder, split lengthwise into two approximately symmetrical parts 26 and 27.

Part 26 is pivotally supported on derrick 13 by two fixed hinges 28. Part 27 is pivotally supported on derrick 13 by hinges 29 which permits upward sliding of the part 27; and by a hinge 30 which rests on a washer 32 on vertically reciprocable rod 33. Washer 32 is keyed to this rod.

40 Note the offset nature of all the hinges; by this is meant that the pivots of the hinges are at a considerable distance from the hinged parts. There is no implication as to the distance of the hinges from each other.

Part 26 carries upwardly engaging jaws 34.

45 Part 27 carries downwardly engaging jaws 35. Each pair of jaws constitutes a lock, to lock the two parts of the tool guide together when in closed position.

50 Each part carries a handle 36, to assist in swinging the part about its pivots.

Hand-lever 31 is pivoted on derrick 13 for swiveling about a horizontal axis, and carries two lugs 38. Connecting lever 39 is pivoted at its bottom end to these lugs, and at its top to the bottom end of reciprocable rod 33.

The opening of my tool guide is accomplished as follows. Starting in the closed position, shown in Figure 3 and in the full lines of Figure 2, hand lever 37 is swung forwardly and upwardly, thus lifting rod 33, and thereby lifting part 27, and disengaging jaws 35 from jaws 34. This position is shown dotted in Figure 2. The lifting means is now in toggle, and may be let go of. Grasping the handle 36 of part 27 it may now be swung aside, into the position shown in Figure 4.

Grasping the handle 36 of part 26, it too may now be swung aside into the position shown in Figure 5.

Note also that the lifting means is in toggle in its lower position.

Other means of locking the two parts together could be employed.

Having now described and illustrated one form of my invention, I wish it to be understood that my invention is not to be limited to the specific form or arrangement of parts herein described and shown, except as specifically covered by my claims.

I claim:

1. A tool guide for a cable-tool drill, comprising two hollow semi-cylindrical parts divided from each other along the major axis of the drill to which the guide is to be attached; hinges to mount one such part to swing horizontally away from the second such part; hinges to mount said second part to swing horizontally away from said first part, and to permit said second part to be moved vertically with respect to said first part; interlocking elements, carried by the two parts, and being such that these elements will be engaged and disengaged by the relative vertical movement of the two parts, when the two parts are closed together; and means for moving the second part vertically with respect to the first part.

2. A tool guide in accordance with claim 1, further characterized by having means for lock-

ing the last mentioned means in disengaged position.

3. A tool guide in accordance with claim 1, further characterized by having means for locking the last mentioned means in engaged position.

4. A tool guide in accordance with claim 1, further characterized by the fact that the hinges are offset.

10 5. A tool guide in accordance with claim 1, further characterized by having means for locking the last mentioned means in both disengaged and engaged positions respectively.

6. A tool guide for a cable-tool drill, comprising: two hollow semi-cylindrical parts, divided from each other along the major axis of the drill to which the guide is to be attached; hinges to mount one such part to swing horizontally away from the second such part; hinges to mount said 15 second part to swing horizontally away from said first part, and to permit said second part to be moved vertically with respect to said first part; interlocking elements, carried by the two parts, and being such that these elements will be engaged and disengaged by the relative vertical movement of the two parts, when the two parts are closed together; and means for moving the second part vertically with respect to the first part; said tool guide being further characterized 20 by the fact that the last mentioned means comprises: a pitman engaging a vertically moveable portion of the hinge of the second part, in such manner that vertical reciprocation of the pitman will raise and lower said second part; a crank to 25 actuate the pitman, said crank and said pitman being so relatively proportioned and located that the crane will lock the pitman in toggle at its extreme lower position and at its extreme upper position; and manual means for rotating the 30 crank.

GEORGE R. WATSON.
